Inventor:

Ernest Tobler

UNITED STATES PATENT OFFICE.

ERNEST TOBLER, OF BRAUNSCHWEIG, GERMANY.

COMBINATION LOCK.

Application filed November 2, 1922. Serial No. 598,643.

To all whom it may concern:

Be it known that I, ERNEST TOBLER, a resident of Braunschweig, Germany, citizen of the Swiss Confederation, have invented 5
5 certain Improvements in Combination Locks, of which the following description, in connection with the accompanying drawings, is a specification, like characters on the drawings representing like parts.

10 This invention relates to a combination padlock of the kind comprising a casing adapted for the reception of the two limbs of a shackle and provided with rotatable, notched rings which in one position lock 15 the shackle by engagement with notches in its limbs and which release the shackle when, by a certain relative adjustment, all the ring notches are set in alignment with each other and with the limbs, the rings being directly 20 superposed and adapted to be transposed with respect to each other for changing the combination.

The object of the invention is to provide 25 additional means for changing the combination of the lock without complicating the structure, and the invention consists in arranging the notches of the shackle limbs in a relatively staggered position and in arranging the ring notches so that a change 30 in the combination can be effected by reversing the shackle and by turning each of the rings over bodily.

Fig. 1 of the accompanying drawings represents a vertical section of the padlock 35 taken on the line *c-d* of Fig. 3,

Fig. 2, a side view of the padlock, and

Fig. 3, a cross-section on the line *a-b* of Fig. 1.

Figs. 4 and 5 are views showing different 40 forms of notching the shackle limbs.

The padlock consists of a casing 3 having a central circular cavity in which a plurality of rings 5, piled directed on each other, are rotatably arranged. There are also two 45 diametrically opposed bores which are adapted to receive the two limbs of a shackle 1 and which slightly encroach on the central cavity so as to allow the rings to engage notches 4^a—4^b made in the limbs of the 50 shackle 1. Notches 4^a—4^b of one limb are staggered relative to the notches 4^c—4^d of

the other limb, and each ring has an elongated circumferential notch 9 in which to admit the full portion of one limb while the ring engages a notch in the opposite 55 limb. The notch 9 allows the ring to be turned through an angle α , and the ring has another notch 8 which, in one position of rotary adjustment of the ring, registers with the opposite limb of the shackle so as 60 to leave the latter disengaged. Each ring is provided, in known manner, with a stud 7 which projects through a slot in the side of the casing and which can be used for adjusting the ring. The position of the stud 65 7 relative to the notch 8 and to the casing slot is such, that the stud determines the 70 unlocking position, i. e., the registration of the notch 8 with the shackle limb, by abutment against one edge of the slot. In Fig. 3 the 75 unlocking movement is anti-clockwise, and it is evident that, by turning the ring over on the other side and reversing the shackle, the unlocking movement will be a clockwise one. By arranging the notch 8 opposite 80 different ends of the notch 9 and altering the position of the stud 7 accordingly, the rings can be made to open in either direction in any given position in the pile, and a suitable combination is made up which must be 85 known for opening the lock. While the combination can be changed by a turning over of the rings and by a reversal of the shackle, as previously described, it can also be changed by piling the rings in a different order or by replacing individual rings 90 by others adapted for unlocking movement in the opposite direction without a reversal of the shackle. As the rings are arranged loosely in direct contact with each other, these changes can be easily effected. The 95 casing is closed by a cover 2 which screws onto a spindle 6 and which is normally locked by the shackle, the spindle being squared to the casing so as to prevent it from being unscrewed.

I claim:

A combination padlock of the character described, comprising a U-shaped shackle having notched limbs, the notches of one 100 limb being staggered relative to those of the other limb, a casing having bores in which

to receive the limbs of the shackle, and a plurality of superposed rings arranged rotatably in said casing so as to encroach on the bores and engage the notches of the shackle limbs, each ring having an elongated notch which registers with the full portion of one limb so as to allow a partial rotation

of the ring through the notch in the opposite shackle limb, the ring having also a notch which, in one end position of the ring, registers with said latter limb so as to allow the shackle to move. 10

ERNEST TORLER.
